UNITED STATES PATENT OFFICE.

FRANK L. BARNEY, OF PRAIRIE DU CHIEN, AND HILBERT E. TAYLOR, OF BLOOMINGTON, WISCONSIN.

DENTAL PLUGGER.

SPECIFICATION forming part of Letters Patent No. 402,294, dated April 30, 1889.

Application filed July 26, 1888. Serial No. 281,091. (No model.)

To all whom it may concern.

Be it known that we, FRANK L. BARNEY, of Prairie du Chien, in the county of Crawford and State of Wisconsin, and HILBERT E. TAYLOR, of Bloomington, in the county of Grant, and in the State of Wisconsin, have invented certain new and useful Improvements in Dental Pluggers; and we do hereby declare that the following is a full, clear, and exact 10 description thereof.

Our invention relates to dental pluggers; and it consists in certain peculiarities of construction and combination of parts, to be hereinafter described with reference to the accompanying drawings, and subsequently 15 claimed.

In the drawings, Figure 1 represents a longitudinal section of a dental plunger constructed according to our invention; Fig. 2, a 20 section taken on line 2 2 of Fig. 1; Fig. 3, a section taken on line 3 3 of Fig. 1; Figs. 4 and 5, detail views of the mallet and shell that form parts of our device; Fig. 6, a partial section view showing another form of instrument employed in connection with our 25 device and the means for actuating said instrument; Fig. 7, an end view of the same; Fig. 8, an end view of the plunger-bore shown in Fig. 1; and Figs. 9 and 10, detail sections 30 showing another means for changing the angle of the instrument.

Referring by letter to the drawings, A represents the outer shell or casing of our dental plunger, and screw-threaded to one end of 35 this shell is an ordinary slip-coupling, B, for attaching the plunger to a dental engine. Screw-threaded to the other end of the shell A is a tip, C, that serves as a bore for a plunger, D, that in one of its forms is provided with a circular head, E, for the strokes 40 of a mallet, to be hereinafter described.

The free end of the tip C is provided with a series of longitudinal notches, b, diametrically opposed in pairs, and designed for the 45 reception of the ends of a pin, c, that passes transversely through the plunger D; or instead of this pin said plunger may be provided with lugs arranged to serve the same purpose.

The bore of the tip is enlarged at its inner 50 end to receive head E of plunger D, and a

spiral spring, F, that surrounds said plunger between its head and a shoulder, d, the latter being formed by said enlargement of the tip-bore. By drawing the plunger out against the tension of spring F the pin or lug c can be 55 shifted from one to another pair of the notches b, to thereby change the angle of a plugging-tool, G, connected to said plunger, and said notches also permit the reciprocation of the plunger within the tip, the construction thus 60 far described being best illustrated in Figs. 1 and 8.

In Fig. 6 we show another form of tip and plunger designed for work on the back side of teeth. The latter form of plunger is reduced 65 for a certain distance from its upper end to receive the spring F, the latter being arranged to exert its force against a sleeve, H, that is slipped onto the inner end of said plunger. The sleeve H is provided with the 70 notches b for the pin or lugs c belonging to the plunger, and said sleeve is also provided with an arm, H', to which is hinged a plate, I, that is in turn pivoted to the tip C by means of a pin, d', as illustrated in Figs. 6 75 and 7.

In the latter form of tip and plunger the angle of the plugging-tool G is changed by pushing in on said tool against the spring F, thereby disengaging the pin or lugs c from 80 one pair of notches and permitting the turning of said tool to bring said pin or lugs into engagement with another pair of said notches.

The plugging-tool attached to the latter form of plunger is held against the back side 85 of a tooth, and by pulling against said tool the plate I is tilted to receive the blow of the mallet.

By Figs. 9 and 10 we show still another form of tip and plunger, the same being intended for use instead of similar parts shown 90 in Fig. 1. In the latter form of tip and plunger the latter is formed with a collar, J, arranged adjacent to the head E, this collar being provided with the notches b and the pin 95 or lug c, arranged to project inward from said tip to engage any one of said notches, according to the angle it may be desirable to set the plugging-tool. To set the plugging-tool, the plunger is drawn down against the spring F 100

to bring the collar out of engagement with the pin or lug *c*, the tool turned to the requisite angle, and the plunger released. The spring *F* forces the plunger back to its normal position to bring another notch into engagement with the pin or lug on the tip.

The mallet *K* in our device is splice joined to a shell, *L*, that is provided with a step, *M*, for the jointed shaft *N*, designed for connection with the dental engine, said shaft being provided with a cam, *O*, that operates in conjunction with another cam or pin, *P*, on one of the mallet-splices. A spring, *Q*, rests on the inner end of the shell *L* and operates to keep the running-cam *O* clear of the mallet cam or pin *P*, this being the normal position of the parts.

The mallet *K* is provided with a recess, *f*, for engagement with the inner arm of a bell-crank lever, *R*, that is fulcrumed to the sides of a box, *g*, that projects from the shell *A*, the latter being slotted at *h* to permit said arm of the bell-crank lever to enter the recess in said mallet. The bell-crank lever *R* is worked by the thumb of the operator to raise the shell *L* against the force of a spring, *S*, that is supported on a washer, *T*, arranged between the opposing ends of the splices belonging to said shell and the mallet, thereby bringing the running-cam *O* more or less into contact with the cam *P*, whereby the lift of said mallet is controlled in proportion to the depression of said bell-crank lever.

The mallet *K* and shell *L* are held against rotation by means of a lug, *i*, that projects inwardly from the shell *A* to engage a slot, *j*, in said shell, and when the mallet is lifted by the action of the cams *O P* the spring *S* forces said mallet back the moment said cams pass out of contact, thereby causing an impact against the head *E* of the plunger.

A slide, *U*, is arranged in the box *g* on the casing *A* and carries a pin, *k*, upon its inner end. When the slide *U* is moved in, the pin *k* thereon comes into position to form a rest for the outer arm of the bell-crank lever *R*, whereby the lift of the latter is limited, and in consequence thereof the mallet has only a slight blow on the plunger-head, because the contact of the cams *O P* is correspondingly limited.

To prevent the shell *L* from leaving the cam-shaft *N* when driven back by the spring *Q*, after being raised by the bell-crank lever *R*, a screw or pin, *V*, is passed through one of the splices of said shell to rest upon said cam *O*, as best illustrated by Fig. 2.

By means of the bell-crank lever *R* the mallet may be started, stopped, or controlled by a slight pressure of the operator's thumb, and the pressure of the mallet-spring being less than is usually the case in dental pluggers of the ordinary construction the parts composing said plunger can be more readily taken apart and put together, and any undue pressure on the connection for the dental engine is not liable to damage the device, from

the fact that the jointed cam-shaft *N* yields to said pressure. In some instances the bell-crank lever *R* may be omitted and the cams *O P* arranged to come in and out of contact with each other at each revolution of the cam-shaft.

Having thus fully described our invention, what we claim as new, and desire to secure by Letters Patent, is—

1. In a dental plunger, the combination of a spring-controlled tool-plunger, a mallet for the plunger, a shell loosely spliced to the mallet, a spring arranged to exert its pressure against said mallet, another spring arranged to exert its pressure against the shell, a cam or pin arranged on one of the mallet-splices, a jointed drive-shaft stepped in said shell and moved back and forth by the latter, and a cam carried by the shaft to come in and out of contact with the cam or pin on said mallet-splice, substantially as set forth.

2. In a dental plunger, the combination of a spring-controlled tool-plunger, a mallet for the plunger provided with a recess, a bell-crank lever fulcrumed to the casing or body portion of the plunger and arranged to engage said recess, a spring arranged to exert its pressure against the mallet, a shell loosely spliced to said mallet, a spring arranged to exert its pressure against the shell, a cam or pin arranged on one of the mallet-splices, a jointed drive-shaft stepped in said shell and moved back and forth by the latter, and a cam carried by the shaft to be brought in and out of contact with the cam or pin on said mallet-splice by a movement of the bell-crank lever, substantially as set forth.

3. In a dental plunger, the combination of a spring-controlled tool-plunger, a mallet for the plunger provided with a recess, a bell-crank lever fulcrumed to the casing or body portion of the plunger and arranged to engage said recess, a sliding plate provided with a rest for the bell-crank lever, a spring arranged to exert its pressure against the mallet, a shell loosely spliced to said mallet, a spring arranged to exert its pressure against the shell, a cam or pin arranged on one of the mallet-splices, a jointed drive-shaft stepped in said shell and moved back and forth by the latter, and a cam carried by the shaft to be brought in and out of contact with the cam or pin on said mallet-splice by a movement of the bell-crank lever, substantially as set forth.

4. In a dental plunger, the combination of a spring-controlled tool-plunger, a tip for the latter, a series of notches, and a pin or lug arranged with relation to the plunger and its tip, whereby the tool carried by said plunger may be set at different angles, and means, substantially as described, for actuating the plunger.

5. In a dental plunger, the combination of a spring-controlled tool-plunger provided with a transverse pin or lug, the plunger-tip provided at its free end with a series of diametrically-opposed notches for engagement

with said pin or lug, whereby the tool carried by said plunger may be set at different angles, and means, substantially as described, for actuating the plunger.

5 6. In a dental plunger, the combination of a tool-plunger, a mallet for actuating the plunger, a drive-shaft, and cams arranged with relation to the mallet and shaft, whereby the revolution of the latter causes an impact 10 of said mallet against said plunger, a bell-crank lever for engagement with the mallet,

and a spring in opposition to the lever, substantially as set forth.

In testimony that we claim the foregoing we have hereunto set our hands, at Blooming- 15 ton, in the county of Grant and State of Wisconsin, in the presence of two witnesses.
